UNITED STATES PATENT OFFICE.

CLARENCE H. TAUBEL, OF RIVERSIDE, NEW JERSEY, ASSIGNOR TO HEMPHILL COMPANY, OF CENTRAL FALLS, RHODE ISLAND, A CORPORATION OF MASSACHUSETTS.

SEAMLESS KNIT, CLOCKED STOCKING AND METHOD OF MAKING SAME.

Application filed July 29, 1926. Serial No. 125,660.

This invention relates to seamless knit, clocked stockings and to the method of making the same.

In order that the principle of the invention may be readily understood, I have in the accompanying drawings illustrated certain embodiments of my invention as characteristic of the fabric thereof, and shall herein describe sufficiently the best mode 10 known to me for practising the method of my invention.

In the drawings:

Fig. 1 is a side elevation of a seamless hose or stocking embodying or containing 15 my invention;

Fig. 2 is an enlarged view in side elevation of a portion of the fabric shown in Fig. 1, and sufficiently indicating the character of the fabric and the manner of producing the 20 clocked effect;

Fig. 3 is a view similar to Fig. 1 but representing a construction which is a modification of that illustrated in Fig. 1;

Fig. 4 represents a portion of the fabric 25 of Fig. 3, but upon an enlarged scale;

Fig. 5 is a view similar to Fig. 3 but of another modification;

Fig. 6 is an enlargement of a portion of the fabric shown in Fig. 5; and

Fig. 7 is a diagrammatic representation 30 constituting a horizontal section taken through the hose or stocking and representing the knitting in of the clocking thread or threads and the floating thereof between 35 the sides of the stocking.

Clocked, seamless knit, stockings have long been upon the market. They are usually produced by introducing the clocking 40 yarns locally as embroidery yarns, as it were. This introduction of the clocking yarns is frequently accomplished by a peculiar action of yarn guides which may be said to wrap the figuring or embroidery yarns about the necessary needles at opposite sides 45 of the machine, as illustrated, for example, in the patent to Frank W. Robinson, No. 1,077,304, November 4, 1913, and that to Heister Seiders, No. 1,505,973, August 26, 1924. It is unnecessary to refer in detail to 50 the means heretofore resorted to for producing a clocked effect in a seamless stocking.

It has long been known that seamless stockings may be provided with vertical 55 stripes of another color of yarn by introducing two yarns and at the proper points

floating one yarn behind the other for a few wales so as to produce a series of longitudinally extending stripes entirely about the stocking. A stocking of such type is disclosed in the patent to Emil A. Hirner, No. 1,062,910, dated May 27, 1913. A characteristic feature of that stocking is the provision of a series of lengthwise extending stripes, the aggregate width whereof is not so great in proportion to the aggregate width of the 60 stripes of plain knitting as substantially to impair the lateral elasticity of the stocking. A stocking so constructed is provided with relatively short lengths of float thread or 65 yarn which therefore need not be cut out.

An additional yarn, usually of the same color as the body yarn, has been knitted into a stocking to form a stripe of relatively narrow width extending lengthwise the 70 stocking from the top of the high splice reinforcement to the welt. Such a stocking is disclosed, among others, in the patent to William J. Longtin, No. 1,353,659, September 21, 1920. The additional yarn 75 constitutes a stripe or reinforcement which simulates the selvage reinforcements for a full fashioned stocking and such additional 80 yarn is cut away at the edges of such stripe or reinforcement.

Among other instances of the introduction 85 of an additional yarn at the back of the stocking, reference may be made to the patent to Robert W. Scott, No. 1,267,126, May 21, 1918, as characteristic of the manner of introducing an additional yarn to cause the 90 appearance of a seam, and also to the patent to Rufus W. Scott, No. 1,491,760, April 22, 1914, as characteristic of the manner of introducing a secondary or additional yarn along two lengthwise extending but closely 95 spaced areas between which such secondary or additional yarn is floated.

The high splice of a circular knit stocking has for more than fifty years been produced by supplying a reinforcing yarn to substantially one half the circle of needles and floating such reinforcing yarn past the other half circle of needles to be reintroduced in this manner course after course at the part of the stocking above the heel. 100 Such floated yarns are necessarily cut out after completion of the stocking. This same method has also been resorted to in the formation of the so-called tapered high splice 105 provided in seamless stockings.

Notwithstanding the fact that it has long been known that a reinforcing yarn may be introduced to a portion of the circle of needles of a circular knitting machine and floated where not so introduced, no one, so far as I am aware, has heretofore produced a seamless knit hose or stocking having a clock effect at opposite sides of the boot portion or ankle (and if desired at opposite 5 sides of the foot) by providing an additional yarn or yarns of color or character contrasting with that of the body thread or yarn, and by floating such contrasting yarn or yarns where not so inter-knitted, to be subsequently cut away.

In a hose or stocking produced in accordance with my invention, the yarn or yarns which contrast as desired in color or character with the body yarn, are introduced at 10 each side to but a relatively few wales, course after course, and are then consistently floated substantially half way around the hose or stocking to be similarly introduced at the opposite side and then after a corresponding 15 number of few wales are again floated substantially half way around the hose or stocking to be again introduced at the side first referred to, this operation being repeated throughout the extent of the 20 clock.

It is desirable and of great importance to introduce the clocking yarn or yarns in such manner that it or they shall appear wholly at the outer or right face of the 25 hose or stocking wherever such yarn or yarns is or are supplied. This I preferably accomplish by such control of the main or body yarn and the clock yarn or yarns either through a difference in tension upon 30 the main yarn and the clocking yarn or yarns, or otherwise, as to insure the throwing of the clocking yarn or yarns to the outer face of the fabric.

In the simplest embodiment of my invention I provide but a single clocking yarn and this is introduced consistently course after course for a comparatively few wales, as, for example about three or four, from the upper end of the clockwise stripe down, 35 if desired, to the commencement of the heel, where the introduction of the clocking yarn is suspended by proper manipulation of its yarn guide, until the heel is completed, after which such clocking yarn is reintroduced 40 and is or may be continued in operation down to the commencement of the toe. In certain variations or modifications of my invention the said clocking yarn may be temporarily thrown out of operation at 45 times so as to produce a break or breaks in the continuity of the clocking stripe, and if desired one or more additional clocking yarns may be thrown in to produce short vertical stripes or a dotted effect adjacent 50 to the main clocking yarn or in substitu-

tion therefor. Other variations or modifications of my invention it is unnecessary to describe or disclose in detail, since with the explanation of the principle of my invention before him a skilled knitter may 70 make the same.

I will now briefly refer to those embodiments of my invention which I have selected for illustration and will describe them with reference to the drawings.

In Fig. 1 I have represented at 1 a circular or seamless knit hose or stocking which obviously may be made of any desired length either as a woman's stocking, or as here shown it may be provided with a ribbed top 80 2 in a manner generally characteristic of a man's hose. Such hosiery is provided with a heel 3 and a toe 4 made by a narrowing and widening operation and with the introduction of an additional yarn or the substitution of another yarn in the making of such heel or toe in a manner not necessary more fully to describe.

The hose or stocking may be knit upon any suitable circular knitting machine as for example a Banner machine of the general type disclosed in the patent to Joshua D. Hemphill, No. 933,443. While obviously the hose or stocking and the clocking yarn or yarns may be of any desired colors, I will for convenience of description only, refer to the body yarn of the hose or stocking as white in color. Such yarn is introduced as the main or body yarn in usual manner, not necessary to describe, and at a desired point,

as, for example, a slight distance below the rib top (if the latter be provided) or at the boot or ankle portion of a woman's stocking, I introduce the clocking yarn or it may be the main clocking yarn which I have represented at 5 and which, for convenience of description, I will refer to as brown in color. This yarn is desirably introduced through a yarn finger positioned side by side with the main yarn finger and movable into and out of action independently thereof, so that when it is desired that the yarn 5 shall not appear in the fabric, the same is floated as indicated at 6, 7 in Fig. 7. Such clocking yarn is so controlled, as by being supplied at a different tension from the main or body yarn of the fabric, or otherwise, that said clocking yarn consistently appears upon the outer face of the stocking in what may be termed a plating effect. Desirably, following the completion of the stocking, the floated yarns 6, 7 are severed in any suitable manner close to both longitudinal edges of the clocking stripe at the inner face of the stocking, but at a sufficient distance from the inner face itself to prevent the ends of the now severed yarns from being drawn through to the outer face.

In the form of my invention shown in Fig. 1, the clocking stripe 5 is continued or re-

sumed at each side of the foot as indicated at 8, and the clocking may consist entirely of the single clocking yarn. It is not necessary that the said clock be of equal width or diameter throughout, as within the scope of my invention it may be of varying widths at different parts, as, for example, by providing a widened head.

If it is desired to produce a head or other widened part, I may, instead of introducing the said brown clocking yarn 5 to an additional number of needles at each side in a number of courses sufficient to constitute such an enlargement, introduce one or more additional clocking yarns to the extent desired. As a convenient form thereof I have in Fig. 1 and in Fig. 2 represented the introduction of a second clocking yarn as at 9 and for convenience of description will refer to this as a black supplemental clocking yarn. Desirably such a yarn is introduced as shown at each side of the brown clocking yarn 5 and may be introduced so as to produce a solid effect or as here shown to provide a spotted or short line or other effect. In said Fig. 1, said black yarn is represented as introduced at each of four wales or groups of wales, and between said wales or groups of wales the said black clocking yarn is desirably floated for the short distance required. When the said black yarn arrives at the vicinity of the brown stripe 5 I may, for simplicity of operation, continue the said black yarn in operation as the characteristic effect of the yarn 5 is not thereby lost, it appearing at the outer surface. I may, if preferred, however, float the said black yarn past the brown yarn if the said brown yarn be itself continued in action when the supplemental or second clocking yarn is employed. The said second clocking yarn 9 is floated from side to side of the stocking, as shown at 9', 9'' in Fig. 10 in the same manner as described with respect to the clocking yarn 5 at 6, 7.

In Figs. 3 and 4, I have represented a modification or variation of my invention. Therein the brown yarn 10 is introduced periodically only instead of continuously throughout the length of the stripe, and where said brown yarn is not introduced I substitute one or it may be more than one other clocking yarn. For example, as shown in Fig. 3, I may at desired points introduce a blue clocking yarn 11 and at other points introduce a black clocking yarn 12. Said other clocking yarns may be so introduced as to provide a solid effect or short line effect or a dotted effect, this being done in the manner described with reference to Fig. 1.

In Figs. 5 and 6, I have represented another modification or variation of my invention. In this instance, I introduce the brown yarn 13 at intervals only, in such manner as to produce a somewhat wider ef-

fect in the nature of short lines slightly spaced apart, and at other points I introduce the blue yarn 14 in a similar manner.

The examples referred to are disclosed as a few forms only of effects that may be secured in the practice of my invention. All said forms are characteristic of my invention in that whether a single clocking yarn is introduced or a plurality of clocking yarns are introduced, it is or they are introduced only to provide a clocking effect, and are introduced for a relatively few wales only, at opposite sides of the stocking, such clocking yarn or yarns being floated from one side of the stocking to the other, and from said other side back again to the first mentioned side throughout the formation of the clocks. Moreover, as hereinbefore stated, such clocking yarn or yarns must be of a character or color, or both, that contrasts with the main or body yarn and must be so controlled, where introduced, as to lie upon the outer face of the stocking, or otherwise be so introduced as a clocking yarn or yarns as to give a solid or characteristic color or effect at the points where such clocking yarn is introduced.

The clocking yarn or yarns is or are not introduced as a reinforcement, but to produce a clocking effect and in obtaining the same, I may rely for contrast upon a difference in color, or in material, or in some distinguishing characteristic depending upon the particular effect to be produced. Obviously within the scope and purpose of my invention a great number of different effects may be produced.

Having thus described certain embodiments of the fabric of my invention and the best mode known to me for practising the method of my invention, I desire it to be understood that although specific terms are employed, they are used in a generic and descriptive sense and not for purposes of limitation; the scope of the invention being set forth in the following claims:

1. A circular knit or seamless stocking composed of a main yarn or yarns and having a contrasting clocking yarn introduced at the opposite sides of the stocking for a few wales only at each of said sides, and therebetween floated from side to side of the stocking throughout the longitudinal extent of the clocks.

2. A circular knit or seamless stocking composed of a main or body yarn and a contrasting clocking yarn or yarns appearing at the outer face of the stocking at the clocking areas only and floated between said areas at the inner face of the stocking for severance at said inner face along the longitudinal edges of each clocking area.

3. A blank for a circular or seamless knit, clocked stocking, said blank being composed of a main or body yarn or yarns and a con-

trasting clocking yarn or yarns appearing upon the outer face only of the stocking at the clocking areas thereof and uninterruptedly floated at the inner face of the stocking from clocking area to clocking area for subsequent removal.

4. That method of knitting a circular knit or seamless stocking which includes supplying the main or body yarn, and at one of the 10 clocking areas introducing a contrasting, clocking yarn in such manner as to cause it to appear at the outer face of the stocking for the comparatively few wales embraced within the width of the clocking area at the 15 point of introduction, then continuing the knitting with the main or body yarn but floating the said clocking yarn to the opposite clocking area and there causing the said 20 yarn to appear upon the outer face of the stocking to substantially the same extent as at the clocking area where first introduced, then floating said clocking yarn back to the first mentioned clocking area, and similarly 25 there reintroducing the same, and continuing this operation through the formation of the clocking areas.

5. That method of knitting a circular knit or seamless stocking which includes supplying the main or body yarn, and at one of the 30 clocking areas introducing a contrasting clocking yarn in such manner as to cause it to appear at the outer face of the stocking for the comparatively few wales embraced within the width of the clocking area at the 35 point of introduction, then continuing the knitting with the main or body yarn but floating the said clocking yarn to the opposite clocking area and there causing said 40 yarn to appear upon the outer face of the stocking to substantially the same extent as at the clocking area where first introduced, then floating said clocking yarn back to the first mentioned clocking area, and similarly 45 there reintroducing the same, continuing this operation throughout the formation of the clocking areas, and removing the floating yarn or yarns from between the clocking areas.

In testimony whereof, I have signed my name to this specification.

CLARENCE H. TAUBEL.
